Primary Examiner — Catherine S Posthauer

(57) **CLAIM**

The ornamental design for a gel polish bottle cap, as shown and described.

DESCRIPTION

FIG. 1 is a front and top perspective view of a gel polish bottle cap, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in an assembled configuration.

(Continued)

The broken lines in the figures illustrate portions of the gel polish bottle cap that form no part of the claimed design.
